UNITED STATES PATENT OFFICE.

ALONZO ALDRICH AND ALBERT L. LARSON, OF BELOIT, WISCONSIN; SAID LARSON
ASSIGNOR TO SAID ALDRICH.

PAPER-MAKING MACHINE.

1,421,752.

Specification of Letters Patent. Patented July 4, 1922.

Application filed May 14, 1921. Serial No. 469,552.

To all whom it may concern:

Be it known that we, ALONZO ALDRICH and ALBERT L. LARSON, citizens of the United States, residing at Beloit, in the county of Rock and State of Wisconsin, have invented a certain new and useful Improvement in Paper-Making Machines, of which the following is a full, clear, concise, and exact description, reference being had to the accompanying drawings, forming a part of this specification.

Our invention relates to paper making machines, and especially to a type of paper machine known as a Fourdrinier machine.

One of the objects of the invention is to provide a simple, practical and advantageous construction of Fourdrinier machine.

Another object of the invention is to provide a construction of Fourdrinier machine in which the wire may be removed or changed in a simple and expeditious manner and with the consumption of comparatively little time.

A still further object of the invention is to arrange for the quick and easy movement of the various parts of the machine necessary to remove and change the wire.

In the accompanying drawings Fig. 1 is a side elevation of a Fourdrinier machine embodying our present invention;

Fig. 2 is a skeleton view of the machine in the process of putting in place a new wire;

Fig. 3 is a cross section on a larger scale of the machine preparatory to removing a wire;

Fig. 4 is a cross section similar to Fig. 3 with the machine adjusted to condition ready for the change, the wire in fact having been removed and the machine being in condition to receive a new wire;

Fig. 5 is a plan view on a similar scale of the machine as shown in Fig. 3;

Fig. 6 is an elevation on an enlarged scale of the left hand end of the machine as shown in Fig. 1;

Figs. 7 and 8 are side elevations on the same scale as Fig. 6 of an intermediate portion of the machine;

Fig. 9 is a similar side elevation of the right hand end of the machine;

Fig. 10 is a cross section taken on line 10-10 in Fig. 7;

Fig. 10^a is an end elevation of one post and track of the machine, as shown in Fig. 10;

Figs. 11 to 23, inclusive, are views of details of construction.

Referring to the drawings, and especially to Fig. 1, we show a Fourdrinier machine having a table A supporting rolls 1, over which the wire B extends and travels. The table A is mounted on pedestals or posts 2, 3, 4, 5 and 6, whereof the pedestals 2 and 6 are at the left and right hand ends of the machine respectively, and the pedestals 3 and 4 are located at intervals between the ends. A deckel strap 7 is shown mounted on wheels 8 and 9 having its lower portion 10 resting on the upper stretch of the wire B and its upper portion 11 mounted on standards 12 and 13. A breast roll 14 is shown at one end of the machine for supporting one end of the wire and couch rolls 15 and 16 at the other end of the machine.

In accordance with our present invention the table A is moved or shifted transversely to its length or it may be said transversely to the direction of movement of the wire B, at a time when it is desired to remove and replace a wire. Certain elements of the machine have to be lifted out of the way to permit this transverse table movement. Other elements have to be adjusted or changed in various ways as will be particularly pointed out hereinafter. Suitable provision has to be made for the support of the table when it is drawn or moved as described, and arrangement has to be made for putting a new wire in place, and then pushing the table back to its normal position, adjusting the wire and the various parts and elements, so that the machine is in normal condition again ready for operation. All this will be described hereinafter.

As an arrangement for permitting the table itself to be moved laterally we show a construction best illustrated in a general way in Figs. 3 and 4. In this arrangement there are shown two sets of beams 18-18 and 19-19, the former of which will be called the back channel tracks or beams and the latter the front channel tracks or beams. These beams are not normally in the positions shown in Figs. 3 and 4, not normally being in a sense a part of the machine, but

are put into position preliminary to shifting the table to change the wire. Each of these beams 18 and 19 is preferably made in the form of a pair of channel beams 20 and 21, as shown in Fig. 8, spaced apart by sleeves 22 and held together by bolts 23. As shown in said Fig. 8 these channel tracks are located in recesses 24 in the various pedestals or posts 2, 3, 4, etc. When the wire changing operation is to take place these various tracks 18 and 19 are pushed into the positions shown, a rear track 18 and a front track 19 for each pedestal 2, 3, 4, 5 and 6. The front tracks 19 are longer than the rear ones 18, so that the former extend well through the front posts or pedestals 2, 3, 4, etc., and are fitted to the rear ones 18 by means of parts 25 (Fig. 10), secured on the tracks 18 and fitting into sockets 26 in the tracks 19.

As a means for holding the front ends of the front tracks 19 there are shown supplemental or temporary posts or pedestals 27 (Figs. 10 and 10^a) which as shown in Figs. 25 3 and 4, are placed at the front or outer ends of the tracks 19. These members 27 are preferably in the form of simple cast pedestals having their lower ends provided with pins 28 to fit into apertures in the floor 30 and having their upper ends provided with screws 29 to adjust the height of the tracks 19 thereon. The tracks 18 are provided with stops 29 for checking the back movement of the table and the tracks 19 are provided with stops 30 for checking the forward movement of the table. To permit the latter movement of the table, it is provided with rear wheels 31 and front wheels 32, (Figs. 3, 4, 8 and 10), the rear wheels 31 being arranged to 40 travel on the tracks 18 and the front wheels 32 to travel on the tracks 19. Wheels 31 and 32 are enclosed in housings at joints of table sections, Figs. 8 and 10. Shafts for said wheels are mounted on opposite ends of adjacent table sections.

As an arrangement for driving said wheels or certain of them, a driving shaft 33 (Fig. 8) is mounted on the table and extended longitudinally thereof substantially from end 50 to end of the same, as shown in Fig. 1. Bearings 34 for the left hand end of said shaft 33 are shown more clearly in Fig. 6, intermediate bearings 36 and 37 in Figs. 7 and 8, respectively, and right hand end bearings 55 in Fig. 9. The drive shaft 33 is provided with pinions 39 and the table wheels 32 are provided with rack teeth 40 meshing with the pinions 39 whereby the rotation of the shaft 33 will rotate all of the wheels 32 and 60 thereby cause the table to be shifted laterally one way or another on the tracks 18 and 19, according to the direction the shaft 33 is rotated.

As a means for rotating the drive shaft 65 33 we show a motor 42, (Fig. 7) which may

be an electric motor mounted upon and carried by the table of the machine near the central post 4, as shown in Fig. 1. This motor 42 is connected through gears 43 and 44 with a drive shaft 45 which carries a worm 46 meshing with a worm wheel 47 (Fig. 10) on the main longitudinally extending drive shaft 33. Thus by the operation of the motor 42 and its train of mechanism the drive shaft 33 may be turned in one direction or another, and the table A shifted laterally one direction or another, according to the direction of rotation of the motor. As an arrangement for adjusting the table A to permit it to be lifted slightly to allow of its lateral motion, we provide lifting devices which are capable of lifting the tracks 18 and 19 slightly and thereby not only adjusting said tracks upwardly against the table wheels 31 and 32, but also adjusting said tracks upwardly to an extent to lift the table slightly from the posts or pedestals 2, 3, 4, etc. These lifting devices which are best shown in Figs. 7 and 10, comprise lifting screws 50—50, one for each post or pedestal, and cams 51, on rock shafts 52 controlled by levers 53, the lifting screws 50 being provided with socket members 54 interposed between them and the cams 51 and resting on the latter. The upper ends of 95 these screws 50 are provided with plates 55 which fit against the lower surfaces of the tracks 18 and 19 and between lugs 56 and 57 thereof, so that a swinging movement of the levers 53 will cause the screws 50 to push 100 upwardly against the tracks 18 and 19 and thereby lift the same. This lifting action is very slight but is sufficient to cause the tracks 18 and 19 to contact with the table wheels 31 and 32 and to push the same upwardly to an extent to lift the table slightly 105 up from the pedestals 2, 3, 4, etc. The lifting screws 50 may be adjusted to certain extents so as to cause them practically to contact with the tracks 18 and 19 before the 110 levers 53 are swung, by turning the threaded sockets 54 relatively to said screws 50.

Thus it will be seen that the rails 18 and 19 may be put in position, as shown in Figs. 3, 4 and 5, and then the levers 53 on the 115 pedestals 2, 3, 4, etc., may be turned so as to lift the table A slightly off from said pedestals and then the motor 42 may be started, turning the wheels 31 and 32 and causing the table to move on the tracks 18 and 19, direction of rotation of the motor being such as to cause the table to move to the left, (Figs. 3 and 10) so that it will move from the position shown in Fig. 3 to the position shown in Fig. 4.

There are also other parts or elements of the machine which must be taken care of in this movement and explanation of these will now be made.

One of these elements is the deckel strap 130

7 and its supporting wheels 8 and 9, in connection with the same the pond walls 60, Figs. 1 and 6. These parts are intended to be lifted by cranes which may engage the 5 wheels 8 and 9 and lift the same above their normal positions, as shown in Fig. 2. The pond 60 is also lifted and the construction by which this is accomplished will now be explained. This pond 60 which is best 10 shown in Figs. 6, 17, and 18, is arranged at the side of the head box 61 and is secured thereto in such manner as to permit the pond 60 to be raised relatively to the box 61, as shown in Fig. 2. To such end the front and 15 rear walls of the pond, the front wall or plate 63 being shown, (Fig. 17) are secured to the adjacent wall 64 of the box 61 by means of clamps 65 (Fig. 17). One end of each clamp 65 rests and acts upon an angle 20 bar 66 secured by bolts 67 to the plate 63 and the other end of each clamp 65 contacts with and acts against a vertically extending strip 68 which is secured as by bolts 69 to the outer side of the tank wall 64. The clamps 25 are held in position by bolts 70 passing through them and into the strips 68. Each clamp 65 has a slot 71 permitting it to have a certain amount of play or longitudinal movement with reference to the bolts 70, and 30 the strips 68 are provided with different apertures 72 into any one of which a bolt 70 may be placed in order to allow a further extend of longitudinal adjustment of the clamps 65. By loosening the bolts 70 the 35 box 61 is bodily elevated. In this connection it may be noted that the forward and back adjustment of the wall or plate 63 is permitted by loosening the clamps 73 so as to permit the sleeve 74 to slide on the cross 40 bars or rods 75 and thereby permit the wall 63 to be moved laterally as desired to accommodate different widths of paper to be made by the machine, the position of the plate 63 determining the length of the slot or opening 45 76 (Fig. 6) through which the pulp or material from the pond is fed on to the wire. This transverse movement of the plate 63 is accomplished by means of a crank handle 77 (Fig. 17) which turns the shaft 78 carrying 50 a gear 79 which meshes with a gear 80 on a shaft 81 which extends upwardly and diagonally across the front of the tank, as shown in Fig. 6, and has its upper end provided with a gear 82 meshing with a pinion 55 83, on a rotary shaft 84. The shafts 78 and 84 have threaded ends 78' and 84', respectively, which engage with the plate 63 or parts thereon, and so adjust said plate laterally when said rods 78 and 84 are turned 60 by the rotation of the crank handle 77. The deckel wheel 8 is mounted on the plate 63, as shown in Fig. 18, the axle 8' of the same having an extension 8'' passing through the wheel and being engaged by a plate 87 held 65 in position by nuts 88 and 89. The shaft 8' fits in a slot 90 by which the wheel 8 may be adjusted vertically, (Figs. 6 and 18). Thus the deckel wheel 8 will move with the pond 60. In order that the upper cross shaft 75 may rise with the pond 60, the bearing 91 70 for the same is made open so that said shaft may be lifted bodily out of said bearing, thereby permitting it and all of its connections to leave the bearing and go with the pond and associated parts. The bearing 90 75 is so located as to permit the pond to swing upwardly about the shaft 75 as a pivot. The other deckel roll 9 will be lifted bodily from its bearings 93 (Figs. 19 and 20) by releasing said screws 94 which screw into the upper parts of said bearings 93, the latter being open at their upper ends or U-shaped, as best shown in Fig. 19. The set screws 94 hold the shafts 9' of the deckel wheels 9 in proper position in the bearings 93 until it 80 is desired to lift the deckel strap and associated parts, in which case the screws 94 will be undone, thereby permitting the shafts 9' to be lifted out of the bearings 93, and the wheels 9 to be lifted bodily by cranes or otherwise with the deckel straps 7 thereon. For longitudinal adjustment the bearings 93 are shown mounted on cross heads 95 which are arranged for sliding movement in standards 96 secured in position by screws 97, said 90 movement being accomplished by rotation of a screw 98 having a hand wheel 99. In this way the deckel strap and its pulleys together with the pond and associated parts, may be lifted bodily, as shown in Fig. 2. 100

Arrangement is also made for adjustment of the couch rolls 15 and 16 to permit the removal of the wire. To such end the upper couch roll 16 is mounted on swinging frame members 100 (Figs. 1, 9 and 15), each of 105 which is adapted to swing upwardly and backwardly about a pivotal connection 101 located at the upper end of a base or body member 102 mounted on the floor close to but separated from the endmost post or pedestal 110 6. The member 100 is provided with a projection 103 by which said member 100 may rest in an elevated position, as shown in Fig. 15. The member 100 is held down in its normal or lowered position, as shown in Fig. 9, 115 by a rod 104 having a turn buckle 105 for longitudinal adjustment, and also having a pivotal joint or connection 106, the upper end of said rod being pivotally connected at 107 with the end portion of the member 100 120 and the lower end of the same being connected by means of a nut 108 with a projection 109 on the member 102. By undoing the nut 108 the rod 104 may be released, thereby permitting the member 100 to be swung upwardly to the elevated position shown in Fig. 15. A swinging bar 110 is pivoted on the projection 109 at 111, and is in engagement with the nut 108, so that said pivoted bar 110 125 will exert downward pressure on the rod 104, 130

tending to hold the roll 16 downwardly on the wire B. A weight 112 is mounted on the bar 110 and arranged to slide on the same so as to adjust the pressure exerted by the rod 104. The couch roll 16 is provided with a scraper blade 113 mounted on a block 114 which is adjustable by means of a screw 115 having a wheel 116 and a stop nut 117. The board 114 is mounted on an adjustable member 118 pivoted at 119 on the end of the member 100 and said member 118 is provided with a projection 120 subject to pressure of a spring 121, which surrounds a rod 122 and is subject to the adjustment of a rotary nut 123, whereby pressure may be exerted on the scraping blade 113. The rod 122 is pivoted at 124 and a smaller and weaker spring 125 is located between the pivot 124 and the member 120 so as to lift the member 120 when the pressure of spring 121 is reduced or released. This blade 113 with all its associated mechanism is lifted bodily and swung upwardly when the member 100 is swung upwardly to lift the couch roll 16. The lower couch roll 15, the one about which the wire B is extended, is arranged so that it can be lifted bodily by a crane or otherwise, as shown in Fig. 15. To such end the bearings or journals 127 at the opposite ends of said roll 15, are mounted loosely on journal blocks 128 so that said bearings 127 may be lifted bodily from the blocks 128, and carried up bodily with the roll 15 itself. Each bearing 127 is provided with dowel pins 130 and the block 128 is provided with apertures to receive said dowel pins. The block 128 on the front side of the machine,—that is the nearest side looking at the machine as in Fig. 1, is pivotally mounted by means of a pivot screw 131, whereby said block 128 may be swung about said pivot to the right, referring to Fig. 9, so that it will come into position at the right hand side of its usual position, as shown in Fig. 15. In this way said block 128 may be moved out of the way of the wire B so as to permit the latter to be slipped on or off from the roll 15. The other or rear bearing 127 for said roll 15 is permanently secured to its block 128', (Fig. 16), and the latter is secured to the base member 102, as by screws 132. The upper part 127' of the back bearing 127, however, is simply pulled down, so that it may be removed and permit the rear end of the axle 15' of the couch roll 15 to be lifted out of said bearing 127. In this way the upper couch roll 16 may be swung upwardly and backwardly entirely out of the way and the lower couch roll 15 may have the wire pulled over it and 60 may be lifted bodily upwardly and to the left, so as to give the wire slack, as shown in Fig. 15.

Another element to receive attention is the wire tightener 135, best shown in Figs. 65 1, 8, 21, 22 and 23. This wire tightener com-

prises a roll 136 adapted to rest upon the wire 2 and tighten the same. The roll 136 is mounted in bearings 137, which are secured to and suspended from sleeves 138 and mounted on vertically arranged adjusting screws 140. These screws 140 are provided at their upper ends with miter gears 141 which mesh with pinions 142 mounted on the opposite ends of a rotary shaft 143 (Fig. 21). A hand wheel 144 controls the shaft 143 so that by turning the hand wheel 144 the pinions 142 will turn the screws 140 and thereby cause the sleeves 138 to be raised and lowered so as to raise and lower the roll 136 and thereby vary the pressure applied by said roll to the wire B. The hand wheel 144 is at the front end of the shaft 143, as shown in Figs. 8 and 21.

Arrangement is made so that this tightening device may be swung to one side, preferably upwardly and to the left, referring to Fig. 8, so as to lift the roll 136 clear of the wire B, and also so that the screw 140 may be out of the way to permit movement of the table relatively to the wire. In the arrangement shown, the shaft 143 serves as a pivotal mounting for the screws 140 and associated parts, and to temporarily hold the whole arrangement in position. A clamp or connection 147 is shown between the lower end of the bracket or frame 148 and the side 5' of the post or pedestal 5, said bracket 147 being secured to the flange 51 by bolts 149 and to the standard or upright 148 by bolts 150. To the bearing 151 bolted to the lower end of the frame 148 and serving as a support and bearing for the lower end of the screw 140, is attached a rope or flexible connector 152 which extends upwardly and around a rotary shaft 153 suspended by a bearing 154 from the table A, whereby by the rotation of said shaft 153 the flexible connector 152 may be wound on the shaft 153 and the tightening device 135 may be swung upwardly and to the left, referring to Fig. 8. The shaft 153 may be turned to accomplish this by means of a hand wheel 156. A cog or ratchet arrangement is provided consisting of a cog wheel 157 and a pivoted dog 158 by engaging the cogs on wheel 157 and thereby holding said shaft 153 in any adjusted position. By this arrangement the tightening device as a whole may be swung upwardly and to the left and held in said elevated position, practically horizontal if desired.

On the table A there is another roll 160 mounted at its right hand end on the bracket 161, as shown in Fig. 9. This roll supports the wire 2 and being mounted on the table A, moves with it. Another roll 162 is arranged below the roll 160 and mounted on a bracket 163 on the endmost post or pedestal 6, as shown in said Fig. 9. This roll 162 being mounted on the pedestal 6, does not move with the table A when the latter is 130

shifted laterally, but remains on the pedestal, as shown in Fig. 2. Another roll 165, (Figs. 1, 2 and 7) is shown mounted on the pedestal 4 and this also supports the lower stretch or 5 reach of the wire B, but does not move with the table being on a pedestal. Other pedestals 166, 167, and 168 are shown (Fig. 1) and these pedestals are respectively provided with rolls 169, 170 and 171, also serving to support 10 the under stretch or reach of the wire B.

Thus it will be seen that by the use of the tracks 18 and 19 and the supplemental track supporting pedestals 27, and by operating the motor 42 so as to rotate the main driving 15 shaft 33, the table may be moved forwardly on to the tracks 19, as shown in Fig. 4, the entire table from one end to the other moving forward in this manner and carrying with it the breast roll 14, the table rolls 10 and the 20 end roll 160, but not taking with it the deckel strap 7 and associated parts, nor the couch rolls 15 and 16, which as previously explained are capable of independent adjustment to permit the movement of the table without 25 their following. Before the table is thus advanced to its forward position, the deckel straps 7, with the deckel wheels 8 and 9, and the pond 60 are lifted bodily as previously explained so that they all clear the table and 30 its wire, as shown in Fig. 2. Also the couch roll 16 is swung up and back and the other couch roll 15 lifted by cranes, as shown in Fig. 2. When the machine is arranged in this way the tracks are put in place, the table 35 with all its attached parts run out on the front tracks as in Fig. 4, and a new wire is put in its place.

To put the new wire in place, it is first slipped on the bottom couch in the usual way, 40 and raised to position 15, (Fig. 2). Pipes are shown in Fig. 2, as 175, 176, 177, 178, 179 and 180, all of these pipes being temporarily held in position at the sides of the pedestals 2, 3, 4, 5, and 6, by means of holding devices 45 such as shown in Figs. 11 and 12. These comprise saddles 181 bolted to the various pedestals by bolts 182 and having seats 183 to receive the pipes, and pins 184 arranged to pass through side arms or projections 185 and attach to the saddles 181 by means of chain 186. These pipes are placed over the lower reach or stretch of the new wire which is strung over the rolls 169, 170, 165, 171 and 162, said rolls supporting the wire and 50 said pipes holding it down, and also over pipes 188 and 189, supported by a rod 190 held in place by bracket 191 at the left hand end of the machine, as shown in Fig. 2. The portion of the new wire between the pipe 188 55 and the couch roll 15 is supported by cranes or other lifts indicated diagrammatically at 192, 193, 194 and 195. When the new wire 60 is thus suspended and arranged, as shown in Fig. 2, it is in condition to allow the table 65 to be moved back in place. It is then lowered

so that it will rest on the table rolls 1, and will encircle the breast roll 14 and being already extended around the couch roll 15, the latter is lowered into its bearings which have first been properly adjusted for it and then 70 the pipes 175, 176, etc., are removed, permitting the lower stretch of wire to rise. The table with the wire on it to this extent is then moved backwardly by operating the motor 42 in a reverse direction, and more or less at the 75 same time the couch roll 15 is lowered, thereby permitting the wire to come into its proper position with the slack taken up and the couch roll 15 adjusted back to its normal position and the couch roll 16 lowered so as to apply tension to the upper 80 stretch. The tightening device 135 is then lowered so as to apply tension to the lower stretch. The deckel straps 7 with their associated parts are then lowered into position 85 and other adjustments made so that the table is back in its place carrying a new wire and the machine is all ready for operation with that new wire. The tracks 18 and 19 are then removed and the operation is completed, and 90 the machine ready for further use.

It will be understood that changes and modifications may be made without departing from the spirit of the invention.

What we claim is:

1. A Fourdrinier machine having a table adjustable laterally as an entity, power means attached to the table for moving the table laterally as a unit, and means for supporting the table in a laterally adjusted 100 position.

2. A Fourdrinier machine having a table adjustable laterally as an entity, means for moving the table laterally as such an entity, said means comprising power devices 105 for imparting movement to the table located at intervals along the length of the same, and means for supporting the table in a laterally adjusted position.

3. A Fourdrinier machine having a table 110 adjustable laterally as an entity, and means for moving the table as such entity comprising rotary members arranged at intervals along the table and adapted when rotated to impart a lateral movement to the 115 table, and power transmitting connection extending longitudinally of the table and arranged to apply power to said rotary members.

4. A Fourdrinier machine having a table 120 adjustable laterally as an entity, and means for moving the table as such entity comprising rotary members arranged at intervals along the table and adapted when rotated to impart a lateral movement to the 125 table, and power transmitting connection extending longitudinally of the table and arranged to apply power to said rotary members, said rotary members comprising wheels adapted to move on transversely ar- 130

ranged tracks and said power transmitting connection comprising a rotary shaft extending lengthwise of the table and gear connected with said wheels.

5 5. A Fourdrinier machine having a table adjustable laterally as an entity, and means for moving the table as such entity comprising rotary members arranged at intervals along the table and adapted when rotated to impart a lateral movement to the table, power transmitting connection extending longitudinally of the table and arranged to apply power to said rotary members, and a motor carried by said table and arranged to drive said power transmitting connection.

10 6. A Fourdrinier machine having a table consisting of a plurality of longitudinal sections connected together to make the 20 table a unitary structure, and power means for moving said structure.

15 7. A Fourdrinier machine having a table consisting of a plurality of longitudinal sections connected together to make a unitary structure means for mounting said table so as to permit its bodily lateral movement as such a unitary structure and power means for moving said table laterally.

20 8. A Fourdrinier machine having a table 30 consisting of a plurality of longitudinal sections connected together to make a unitary structure means for mounting said table so as to permit its bodily lateral movement as such a unitary structure, wheels located at intervals along the length of said table and adapted to support the same and move it laterally and power means for moving said table laterally.

25 9. A Fourdrinier machine having a table 35 consisting of a plurality of longitudinal sections connected together to make a unitary structure, means for mounting said table so as to permit its bodily lateral movement as such a unitary structure, wheels located at intervals along the length of said table and adapted to support the same and move it laterally, said wheels being located at the joints of said sections and power means for moving said table laterally.

40 10. A Fourdrinier machine having a table 45 consisting of a plurality of longitudinal sections connected together to make a unitary structure, means for mounting said table so as to permit its bodily lateral movement as such a unitary structure, wheels located at intervals along the length of said table and adapted to support the same and move it laterally, said wheels being located at the joints of said sections, a rotary driving shaft extending lengthwise of the table and connected with said wheels, and means for driving said rotary shaft.

45 11. A Fourdrinier machine having a table 50 consisting of a plurality of longitudinal sections connected together to make a uni-

55 tary structure, means for mounting said table so as to permit its bodily lateral movement as such a unitary structure, wheels located at intervals along the length of said table and adapted to support the same and move it laterally, said wheels being located at the joints of said sections, a rotary driving shaft extending lengthwise of the table and connected with said wheels, and a power generator mounted on the table and arranged to drive said rotary shaft.

60 12. A Fourdrinier machine comprising a table composed of a plurality of longitudinal sections connected together at their ends so as to form a unitary structure, supporting wheels located at the ends of said table and mounted at the joints between the several sections, the intermediate wheels being located between adjacent sections and each wheel being supported by and connected with such adjacent sections, a rotary driving shaft extending lengthwise of the table and gear connected with said supporting wheels, an electric motor mounted on the table and having a worm and wheel connection with said shaft, and posts or pedestals supporting said table and having a loose connection therewith adapted to permit the table to be raised from the posts or pedestal and moved laterally with respect thereto.

65 13. A Fourdrinier machine comprising a table composed of a plurality of longitudinal sections connected together at their ends so as to form a unitary structure, supporting wheels located at the ends of said table and also at the joints between the several sections, the intermediate wheels being located between adjacent sections and each wheel being supported by and connected with such adjacent sections, a rotary driving shaft extending lengthwise of the table and gear connected with said supporting wheels, an electric motor mounted on the table and having a worm and wheel connection with said shaft, and posts or pedestals supporting said table and having a loose connection therewith adapted to permit the table to be raised from the posts or pedestals and moved laterally with respect thereto, and rails or tracks arranged for insertion in recesses formed in said posts or pedestals below said supporting wheels to permit the lateral movement of the table by the travel of said supporting wheels on said rails or tracks.

70 14. In a Fourdrinier machine, a table composed of a series of longitudinal sections, means for connecting said sections together comprising cross members extending crosswise of the table and connected to the opposite sides thereof, and supporting wheels located at the junctures of said sections and confined in covered spaces provided by said cross members.

15. In a Fourdrinier machine, a table composed of a plurality of longitudinal sections connected together to form a unitary structure, in combination with supporting 5 wheels located at the junctures of said sections and confined in spaces between adjacent sections, each of said supporting wheels being provided with a supporting shaft having its opposite ends mounted upon end 10 portions of said adjacent sections.
16. In a Fourdrinier machine, a table composed of a plurality of longitudinal sections connected together to form a unitary structure, in combination with supporting 15 wheels located at the junctures of said sections and confined in spaces between adjacent sections, each of said supporting wheels being provided with a supporting shaft having its opposite ends mounted 20 upon end portions of such adjacent sections, and means for rotating said supporting wheels comprising a rotary shaft extending longitudinally of said table and gear connected with said wheels.
25. 17. In a Fourdrinier machine, a table composed of a plurality of longitudinal sections connected together to form a unitary structure, in combination with supporting wheels located at the junctures of said sections and confined in spaces between adjacent sections, each of said supporting wheels being provided with a supporting shaft having its opposite ends mounted upon end 30 portions of such adjacent sections, means 35 for rotating said supporting wheels comprising a rotary shaft extending longitudinally of said table and gear connected with said wheels, and a power generator mounted on said table substantially midway between 40 the ends thereof and connected with said shaft.
18. In a Fourdrinier machine, a table composed of a plurality of longitudinal sections connected together to form a unitary structure, in combination with supporting 45 wheels located at the junctures of said sections and confined in spaces between adjacent sections, each of said supporting wheels being provided with a supporting shaft 50 having its opposite ends mounted upon end portions of such adjacent sections, means 55 for rotating said supporting wheels comprising a rotary shaft extending longitudinally of said table and gear connected with said wheels, and bearings for said shaft at substantially the ends of the table and at the points of juncture of said sections thereof.
60. 19. The combination with the head box, of a pond attached to the upper end of one side of the box, and means for adjustably securing the pond walls to the box comprising side strips secured to the side walls of the pond and clamping members for clamp- 65 ing said strips to the adjacent portions of the box wall, said clamping members being adapted when loosened to permit the vertical adjustment of said pond strips and thereby permit the vertical adjustment of the side walls, and consequently the entire body 70 and bottom of the pond.
20. The combination with the head box, of a pond attached to the upper end of one side of the box, and means for adjustably securing the pond walls to the box comprising side strips secured to the side walls of the pond and clamping members for clamp- 75 ing said strips to the adjacent portions of the box wall, said clamping members being adapted when loosened to permit the vertical adjustment of said pond strips and thereby permit the vertical adjustment of the side walls, and consequently the entire body 80 of the pond, said clamping members comprising clamps 65 and bolts 70 holding 85 said clamps in position with one end of each clamp against said pond strips and the other end against the box wall.
21. The combination with the head box and pond supported thereby and located 90 adjacent one side wall thereof, said pond having its side walls provided with angle strips 66 bolted to the pond by bolts 67, the box wall being provided with vertical strips 68 against which the other portions 95 of said angle strips 67 are in contact, said strips 66 being vertically adjustable with reference to the strips 68, clamps 65 arranged at intervals up and down the strips 66 and 68 and having one end of each clamp 100 in contact with a strip 66 and the other end in contact with a strip 68, and bolts 70 passed through the clamps 65 and engaging the strip 68.
22. The combination with the head box 105 and pond associated therewith, said pond having a laterally adjustable side wall, of means whereby said side wall may be adjusted laterally and means whereby said pond may be adjusted vertically with said 110 side wall in different adjustments.
23. The combination with the head box and pond associated therewith, said pond having a laterally adjustable side wall, of 115 means whereby said side wall may be adjusted laterally and means whereby said pond may be adjusted vertically with said side wall in different adjustments, said last mentioned means comprising an end piece on said side wall mounted for vertical adjustment with reference to the box wall, and means for clamping said member to the box wall in different positions to which it may be adjusted by different lateral adjustments of said pond wall.
24. The combination with the head box 120 and pond associated therewith, said pond having a laterally adjustable wall, an

- means whereby said wall may be vertically adjusted relatively to the box when said wall is in different lateral adjustments.
25. The combination with the head box and pond associated therewith, said pond having a laterally adjustable wall, and means whereby said wall may be vertically adjusted relatively to the box when said wall is in different lateral adjustments, said 5 means comprising an end piece on said wall and means for detachably securing said end piece to said box wall in different positions to which it may be adjusted by different lateral adjustments of said wall.
- 10 26. The combination with the head box and pond associated therewith, said pond having a laterally adjustable wall, and means whereby said wall may be vertically adjusted relatively to the box when said wall is in different lateral adjustments, said 15 means comprising an end piece on said wall and means for detachably securing said end piece to said box wall in different positions to which it may be adjusted by different lateral 20 adjustments of said wall, said last mentioned means comprising clamping members adapted to grip said end piece and hold the same in position in its different adjustments.
- 25 27. The combination with the head box and pond associated therewith, said pond having a laterally adjustable wall, and means whereby said wall may be vertically adjusted relatively to the box when said wall is in different lateral adjustments, said 30 means comprising an end piece on said wall and means for detachably securing said end piece to said box wall in different positions to which it may be adjusted by different lateral 35 adjustments of said wall, said last mentioned means comprising clamping members adapted to grip said end piece and hold the same in position in its different adjustments, said 40 clamping members being provided with longitudinal slots to permit their being used in different longitudinally adjusted positions.
- 45 28. The combination with the head box and pond associated therewith, said pond having a laterally adjustable wall, and 50 means whereby said wall may be vertically adjusted relatively to the box when said wall is in different lateral adjustments, said means comprising an end piece on said wall and means for detachably securing said end 55 piece to said box wall in different positions to which it may be adjusted by different lateral 60 adjustments of said wall, said last mentioned means comprising clamping members adapted to grip said end piece and hold the same in position in its different adjustments, said clamping members being provided with longitudinal slots to permit their being used in different longitudinally adjusted positions, and the box wall being provided with
- means for engaging said clamping members at different longitudinal positions.
29. The combination of a head box having one of its walls provided on its outside with a vertically extending strip 68, a pond associated with said box and having one of its side walls made laterally adjustable and provided with an angle member 66 secured to said wall by bolts 67, and having its flange portion in contact with said strip 68, clamps 65 arranged at intervals up and down the flange 66 and strip 68, each clamp having one of its ends against the flange 66 and its other end against the strip 68, bolts 70 passing through the clamps 65 and engaging apertures in the strip 68, said strip 68 having different apertures for the bolt 70 located in laterally different positions, and means whereby the wall of the pond extending crosswise of its said movable wall, may be longitudinally adjusted to accommodate the lateral movements of said adjustable wall.
30. The combination with the table of a deckel wheel bearing mounted thereon, said bearing being adapted to permit the bodily separation of the deckel wheel from the bearing, said bearing having an open top to permit the deckel wheel shaft to be lifted out of it, and means for temporarily preventing the shaft from leaving the bearing, said means comprising a threaded bolt passing through the bearing wall and adapted to engage said shaft.
31. The combination of a table mounted for bodily lateral movement to one side of its normal position to facilitate changing the wire, means for moving the table and for supporting same during such bodily lateral movement and couch rolls supported by a frame which is separate from and independent of the devices for supporting the table.
32. A machine of the class specified having a laterally removable table and also having a couch roll housing opening toward the wire.
33. The combination with a couch roll of a blade for scraping the same, and means for applying spring tension to said blade to hold it against said roll, said means comprising a pivoted member carrying the blade and spring means applied to said member for adjusting its tension.
34. The combination with a couch roll of a blade for scraping the same, and means for applying spring tension to said blade to hold it against said roll, said means comprising a pivoted member carrying the blade and spring means applied to said member for adjusting its tension, said spring means comprising a pair of springs one on each side of said member and means for adjusting said springs.

35. The combination with a couch roll of a blade for scraping the same, and means for applying spring tension to said blade to hold it against said roll, said means comprising a pivoted member carrying the blade and spring means applied to said member for adjusting its tension, said spring means comprising a pair of springs one on each side of said member and means for adjusting said springs, and means for adjusting said blade relatively to said member.
36. The combination with the lower couch roll of means for permitting said roll and bearings to be bodily lifted from its bearing supports, and means whereby one bearing support may be swung on a vertical axis to one side of its normal position.
37. The combination with the lower couch roll of a journal box 127 for one end of the same, said journal box being loosely mounted on a support and having dowel pins adapted to fit in apertures in said support.
38. The combination with the lower couch roll of a journal box 127 for one end of the same, said journal box being loosely mounted on a support and having dowel pins adapted to fit in apertures in said support, said support being pivotally mounted at one side so as to permit it to be swung to that side of its normal position.
39. The combination with the lower couch roll of a journal member 127 for one end of the roll, said journal member 127 being loosely mounted to permit it to be bodily lifted and a journal member 127 having an upper member 127^a which may be lifted from the member 127.
40. The combination with the table of a wire tightener carried thereby, said tightener comprising a roll adapted for mounting on the wire and means for vertically adjusting said roll to free it from the wire.
41. The combination with the table of a wire tightener carried thereby, said tightener comprising a roll adapted for mounting on the wire and means for vertically adjusting said roll, and means for swinging said roll upwardly to free it from the wire.
42. The combination with the table of a tightener comprising a roll adapted to be mounted on the wire and means for swinging said roll upwardly to free it from the wire.
43. The combination with the table of a tightener comprising a roll for resting on top of the lower stretch of the wire, an adjustable bearing for said roll, means whereby said bearing may be raised and lowered and means whereby the roll, bearing and adjusting means may be swung bodily in an upward and downward manner.
44. In a Fourdrinier machine, a wire tightener comprising a roll, bearings for the opposite ends of the same, vertically ar-
- ranged screw threaded members carrying 65 said bearings, frames holding the upper and lower ends of said threaded members, a cross shaft extended between said frames and mounted in the upper ends of the same, said cross shaft being gear connected with the 70 upper ends of said threaded members, means whereby said cross shaft may be rotated, and means for bodily adjusting the cross shaft.
45. In a Fourdrinier machine, a wire tightener comprising a roll, bearings for the 75 opposite ends of the same, vertically arranged screw threaded members carrying said bearings, frames holding the upper and lower ends of said threaded members, a cross shaft extended between said frames and 80 mounted in the upper ends of the same, said cross shaft being gear connected with the upper ends of said threaded members, and means whereby said cross shaft may be rotated, said frame being arranged to swing 85 about said cross shaft as a pivot.
46. In a Fourdrinier machine, a wire tightener comprising a roll, bearings for the opposite ends of the same, vertically arranged screw threaded members carrying 90 said bearings, frames holding the upper and lower ends of said threaded members, a cross shaft extended between said frames and mounted in the upper ends of the same, said cross shaft being gear connected with the 95 upper ends of said threaded members, and means whereby said cross shaft may be rotated, said frame being arranged to swing about said cross shaft as a pivot, and means whereby said frames may be swung vertically and held in an upwardly swung position.
47. In a Fourdrinier machine, a wire tightener comprising a roll, bearings for the opposite ends of the same, vertically ar- 105 ranged screw threaded members carrying said bearings, frames holding the upper and lower ends of said threaded members, a cross shaft extended between said frames and mounted in the upper ends of the same, said cross shaft being gear connected with the 110 upper ends of said threaded members, means whereby said cross shaft may be rotated, said frame being arranged to swing about said cross shaft as a pivot, and means whereby said frames may be swung vertically and held in an upwardly swung position, said 115 means comprising a windlass mounted on the under side of the table and a flexible connector extending between said windlass and the lower end of the frames.
- In witness whereof, we hereunto subscribe our names this 21st day of April, A. D. 1921.

ALONZO ALDRICH.
ALBERT L. LARSON.
